CLOSURE FOR JARS AND SIMILAR CONTAINERS

Franz Luenz, Chicago, Ill., assignor to Edward C. McLean, Chicago, Ill.

Application February 13, 1941, Serial No. 378,749

9 Claims. (Cl. 215—45)

The invention relates to improvements in closures for jars and other containers and more particularly to a closure of the type adapted to be repeatedly applied to and removed from a container.

One object of the invention is to provide an improved closure of the above general character which can be easily applied and removed without the use of tools by a simple manual operation and without the slightest impairment of 10 the effectiveness of the closure upon reapplication to the container.

Another object is to provide a composite closure of novel and advantageous construction in which the parts are always held in assembled relation.

It is also an object of the invention to provide a reusable closure for jars, bottles, cans and other containers which is neat and attractive in appearance, efficient and reliable in operation, and relatively inexpensive to manufacture.

Other objects and advantages of the invention will become apparent from the following detailed description of the preferred embodiment illustrated in the accompanying drawing in which:

Figure 1 is a perspective view of a closure embodying the features of the invention, the closure being shown as applied to a conventional glass jar.

Fig. 2 is a plan view of the closure with the central portion of the outer member or cap cut away to show the latching mechanism.

Fig. 3 is a vertical sectional view of the closure taken along the line 3—3 of Fig. 2 showing the outer member in locking position.

Fig. 4 is a fragmentary sectional view taken along the same line as Fig. 3 but showing the outer member withdrawn to release position.

Fig. 5 is a perspective view of the inner or cover member of the device.

Fig. 6 is a fragmentary sectional view taken along the line 6—6 of Fig. 2.

While the invention is susceptible of various modifications and alternative constructions, I have shown in the drawing and will herein describe in detail the preferred embodiment, but it is to be understood that I do not thereby intend to limit the invention to the specific form disclosed but intend to cover all modifications and alternative constructions falling within the spirit and scope of the invention as expressed in the appended claims.

For the purpose of illustration, the invention has been shown as applied to a conventional

Mason jar 10 having an opening or mouth 11 in a restricted neck portion 12. The neck portion is provided on its outer surface with ribs 13 constituting threads for receiving the usual screw top. Encircling the neck portion of the container below the ribs 13 is an annular sealing flange or bead 14 which provides a seat for a jar ring or gasket of the well known type. In the present instance the downwardly facing shoulder presented by the bead is utilized to lock the closure in place on the container. It will be understood, of course, that the improved closure may be used with bottles, cans, or any other similar container having suitable means for locking the cover member in sealing position thereon.

In its preferred form, the improved closure comprises an inner member or cover 15 and an outer member or cap 16 assembled in telescoping relation. The inner member is shaped to fit over the mouth of a container to close the same and is formed with a depending flexible or resilient skirt portion 17 adapted to encircle the neck of the container. The outer member is similar in shape to the inner member having a peripheral side wall 18 adapted to fit snugly over the skirt portion of the cover member and operative to force the same into locking engagement with the wall of the container when the cap is pressed down substantially to the position shown in Fig. 3 of the drawing. When the cap member is moved upwardly to the position shown in Fig. 4, the skirt portion of the cover is freed for flexing movement. The cap is retained in either the locking or the released position by means of a novel latch mechanism 19 enclosed in a compartment formed between the end portions of the cover and cap members, the mechanism having means accessible exteriorly of the cap for manually releasing the same.

In the particular closure illustrated, the inner cover member 15 is stamped or drawn from sheet metal to provide an end wall 21 and a peripheral side wall which constitutes the skirt portion of the member. The end wall is preferably inwardly offset from the top edge of the side wall thus leaving an encircling upstanding flange 22 to define the compartment for the latching mechanism. To provide the desired resiliency, the skirt portion 17 of the cover member is slotted at its lower edge to form a series of spaced, relatively narrow fingers 23 adapted to extend along the neck of the container. The free end of each finger is curled inwardly, preferably in a double roll 24 for yieldably gripping the down-

wardly facing shoulder provided by the bead 14 of the container. A gasket 25 of cork, rubber or other suitable material between the end wall of the cover and the top of the container insures effective sealing of the same.

As the peripheral wall 18 of the cap member 16 should be relatively rigid to carry out its intended function, this member may be stamped or drawn from sheet metal if desired. As herein shown, the wall is of generally cylindrical shape and is closed at its upper end by a top wall 26. The top wall is preferably formed with a substantially flat annular outer edge portion 27 adapted for seating on the flange 22 of the cover member while the central portion is domed as indicated in Fig. 3 to provide ample clearance for the latch mechanism. The peripheral wall 18 is of sufficient diameter to fit snugly over the skirt portion of the cover member so that the cap may move freely between the lower or locking position and the upper or release position shown in Figs. 3 and 4 of the drawing respectively. A bead 28 formed around the lower edge of this wall serves to strengthen it and provides convenient means for manually gripping the cap to move it from one position to the other.

The latch mechanism 19 in its preferred form comprises a pair of latch elements 31 and 32 herein shown as flat metal stampings each having a generally rectangular body portion from one edge of which projects a pair of laterally spaced latch lugs 33. The elements are adapted to be assembled in opposed relation, that is, with the latch lugs facing outwardly and are slidably held in this relation by means of an elongated offset tail piece 34 projecting rearwardly from one element and engaging in spaced guide sockets on the other element. The sockets are conveniently formed by striking up tabs 35 from opposite side edges of the element and bending the respective tabs upwardly and inwardly as shown in Fig. 6. Projecting from the outer edge of each latch element, preferably midway between the latch lugs 33, is an elongated tongue 37 having its outer end bent upwardly as at 38 to provide a finger grip for manipulating the latch mechanism. Suitable spring means is provided for yieldably urging the latch elements apart. This means as herein shown comprises a coiled compression spring 39 interposed between a shoulder on the tail piece 34 and the adjacent end of the latch element 32, the spring being held in place by the tail piece which it encircles.

In the particular closure illustrated, the latch mechanism is installed within the compartment defined by the wall 21 and flange 22 of the cover member 15. To this end the flange 22 is provided at opposite sides with spaced apertures 41 (Figs. 5 and 6) adapted to slidably receive the latch lugs 33. Midway between the respective pairs of apertures are slots 42 and 43 for receiving the tongues 37.

To facilitate assembly, the slot 43 is dimensioned to receive the bent up portion 38 of the tongue when the associated latch element is in its normal position. Thus, with the latch elements 31 and 32 and spring 39 assembled as a unit, the bent up portion of one of the tongues 37 may be hooked into the slot 42 and the assembly rocked downwardly until it lies flat on the wall 21. In this operation the latch elements are pressed together against the action of the spring 39 until the end of the other tongue 37 clears the inner edge of the flange 22. Upon release, the spring acts to project the lugs 33 and

tongues 37 through the apertures and slots provided for their reception.

As will be seen by reference to Figs. 1 and 2, the peripheral wall 18 of the cap member is provided on each side with upper and lower sets of apertures 46 and 47 spaced apart circumferentially of the wall to receive the latch lugs 33. The sets of apertures, in turn, are spaced apart vertically so that the upper set 46 aligns with the apertures 41 of the cover member when the cap is moved into the locking position shown in Fig. 3. The lower set of apertures 47 aligns with the apertures 41 when the cap member is moved to the upper or release position shown in Fig. 4. Vertical slots 48 in the wall 18 between the pairs of apertures accommodate the tongues 37 which are arranged to project substantially beyond the outer surface of the wall. Accordingly, upon relative movement of the cap and cover members to either their locking or release positions, the spring 39 will operate to project the latch lugs 33 through the aligned apertures in the respective members and thus positively latch the members together. To release the latch so that the members may be shifted from one position to the other, the finger grips 38 are simply pressed together to force the latch elements inwardly and thus retract the latch lugs from the apertures. No tools are required for this purpose and the effectiveness of the device is in no way impaired by repeated use.

It will also be seen that, with this arrangement the inner and outer members of the closure are always held in assembled relationship so that there is no chance of one of the parts being misplaced. However, the members may be quickly and easily disassembled and reassembled without the use of tools by simply forcing the finger grip 38 into the slot 43 of the cover member. This allows the tongue 37 to clear the lower edge of the slot 48 so that one side of the cover member may be readily withdrawn from the cap. The other tongue may then be withdrawn by simply tilting the cover member sufficiently to clear the lower edge of the cap. The reverse procedure is followed in assembling the inner and outer members.

When the closure is to be applied to a jar or other container, the cap member is set in its upper or release position as shown in Fig. 4 and the cover member is slipped over the mouth of the container. Due to the flexible character of the skirt portion of the cover member, the rolls 24 are enabled to slide over the bead 14 and engage the downwardly facing shoulder which it presents. The latch mechanism is then released by pressing the finger grips 38 between the thumb and finger and the cap 16 is pushed down into the lower or locking position shown in Fig. 3. In this position, the peripheral wall of the cap forces the skirt portion of the cover inwardly and the rolls 24 thus ride over the inclined shoulder of the bead 14 and tend to draw the cover down tightly over the mouth of the container.

The cover member is positively retained in the locking position by the latch lugs 33 projecting through the aligned apertures 41 and 46 in the flange 22 and wall 18. Thus accidental displacement of the closure is effectually prevented. To remove the closure it is only necessary to release the latch mechanism by pressing in the finger grips 38 whereupon the cap member may be shifted to its upper or release position. This can be done conveniently by gripping the bead 28. The cover member may then be lifted from the

container, the skirt portion flexing to permit the rolls 24 to ride over the bead 14.

It will be apparent from the foregoing that the invention provides a reusable closure of novel and advantageous construction for jars, bottles, cans and other containers. The parts employed are of simple form and lend themselves readily to production by simple stamping operations. Moreover, they may be assembled with a minimum of labor which further contributes to low manufacturing costs. Through the medium of the novel latch mechanism provided by the invention, the inner and outer members of the closure may be locked in one position to effectually prevent removal from the container or in an alternate position permitting convenient removal and reapplication to the container. Latching and unlatching of the closure members is effected easily without the use of tools and without the slightest impairment of the closure for reuse.

I claim as my invention:

I claim as my invention:

1. A closure for containers comprising, in combination, a generally cup-shaped cover adapted to fit over the open end of the container, said cover having a flexible skirt portion engageable with the walls of the container, a sleeve-like cap assembled in telescoping relation with said cover and movable into a position to force the skirt portion into locking engagement with the container, a pair of latch members slidably supported on said cover for movement radially thereof, said cap having apertures positioned to receive said latch members when the cap is moved into locking position, spring means yieldably urging said latch members into the apertures, and manually engageable means for retracting the latch members to free the cap for movement into a position to release the cover for removal from the container.

2. A closure for a jar or similar container comprising, in combination, a generally cup-shaped inner member adapted to close the mouth of the jar, said member having a depending skirt portion terminating in a flexible edge adapted to engage a downwardly facing shoulder formed on the jar, an outer member having a peripheral side wall dimensioned to fit over said inner member and operative in one position to force the flexible edge of the skirt portion into locking engagement with the shoulder on the jar, and means for latching said outer member in said one position including a pair of members having oppositely facing latch lugs adapted to be projected through aligned apertures in the skirt portion of the inner member and the peripheral wall portion of the outer member.

3. A closure for a jar or similar container comprising, in combination, an inner member having a top wall shaped to close the mouth of the jar and a depending flexible skirt portion extending along the sides of the jar, an upstanding flange encircling said top wall to form therewith a shallow compartment, an outer member having a top wall adapted to cover said compartment and a peripheral side wall dimensioned to fit snugly over the skirt portion of the inner member, said members being relatively movable from one position in which the skirt portion of the inner member is forced into locking engagement with the sides of the jar to an alternate position in which the skirt portion is released for flexing movement to allow removal from the jar, and latch mechanism enclosed in said compartment for releasably latching said members in either position.

4. A closure for a jar or similar container comprising, in combination, an inner member having

a top wall shaped to close the mouth of the jar and a depending flexible skirt portion extending along the sides of the jar, an upstanding flange encircling said top wall to form therewith a shallow compartment, an outer member having a top wall adapted to cover said compartment and a peripheral side wall dimensioned to fit snugly over the skirt portion of the inner member, said members being relatively movable from one position in which the skirt portion of the inner member is forced into locking engagement with the sides of the jar to an alternate position in which the skirt portion is released for flexing movement to allow removal from the jar, and latch mechanism including a plurality of latch elements disposed in said compartment each having a plurality of latch lugs yieldably urged into apertures in said flange, the peripheral wall of said outer member having sets of apertures spaced apart to align with the apertures in said flange and receive the latch lugs when the members are set in either of said positions.

5. A latch mechanism for closures having generally cup-shaped inner and outer members arranged in telescoping relation, said mechanism comprising a pair of flat metallic elements supported in opposed relation on one of the members, each element having at one edge a pair of laterally spaced lugs adapted to be projected 25 through aligned apertures in the members to latch the same in predetermined fixed relation, a tongue extending rearwardly from one element over the other element, spaced guide sockets on 30 said other element for slidably receiving said tongue, and spring means yieldably urging said elements into latching engagement with the 35 members.

6. A latch mechanism for closures having generally cup-shaped inner and outer members arranged in telescoping relation, said mechanism comprising a pair of flat metallic elements supported in opposed relation on one of the members, each element having at one edge a pair of laterally spaced lugs adapted to be projected through aligned apertures in the members to latch the same in predetermined fixed relation, spring means yieldably urging said elements into latching engagement with the members, and an extension on each element accessible exteriorly of the outer member for manually retracting the elements from latching engagement with the members.

7. A latch mechanism for closures having generally cylindrical inner and outer members assembled in telescoping relation, said mechanism comprising a pair of latch elements slidably supported at one end of the inner member for movement radially thereof, latch lugs on the outer edges of said elements adapted to be projected through aligned apertures in the members to latch the same in predetermined fixed relation, means yieldably urging said elements into latching position, and manually operable means accessible exteriorly of the closure for retracting said elements from latching position.

8. A closure for a container comprising, in combination, an inner member adapted to close the container and having a depending flexible skirt portion, a cap member shaped to fit over 70 said cover member, means on the cap member operative to force the skirt portion of the cover member inwardly against the walls of the container, said skirt portion and the container having cooperating means for holding the cover 75 member in sealing engagement with the con-

tainer, a plurality of slidable elements having latch lugs engageable in aligned apertures in the respective members to lock the members together, each of said elements having a part accessible for manual actuation to release the members.

9. A closure for containers comprising, in combination, a cover member shaped to close the mouth of a container and having a depending flexible skirt portion projecting along the wall of the container adjacent the mouth thereof, a cap member adapted to fit over said cover member in telescoping relation for movement between lock-

ing and releasing positions, said cap member having a part adapted to extend over said skirt portion and force the same inwardly into engagement with the wall of the container when the cap member is in the locking position, said part being withdrawn from overlapping relation to said skirt portion to release the same from locking engagement with the container when the cap member is moved to the releasing position, an interengaging latch means on said cover member and said cap member operative to releasably latch the cap member in each of said positions.

FRANZ LUENZ.
